WRINGER

Ernest J. Schuda, Erie, Pa., assignor to Lovell Manufacturing Company, Erie, Pa., a corporation of Pennsylvania

Application January 3, 1931. Serial No. 506,331

10 Claims. (Cl. 68—32)

This invention is designed to improve the wringer structure, particularly with relation to forming a proper support for the lower roll bearings. Features and details of the invention 5 will appear from the specification and claims.

A preferred embodiment of the invention is illustrated in the accompanying drawing as follows:—

Fig. 1 shows a front elevation of the wringer, 10 partly in section.

Fig. 2 a central vertical section on the line 2—2 in Fig. 3.

Fig. 3 an enlarged section on the line 3—3 in Fig. 2.

Fig. 4 a section similar to Fig. 2 showing the 15 manner of assembling the parts.

Fig. 5 a perspective view of the bearing support.

Fig. 6 a section on the line 6—6 in Fig. 2.

The frame is made up of a base 1, this being 20 of channel form, side stiles 2 of box form and a top bar 3. These are all formed of sheet metal. The wringer has the usual lower wringer roll 4, upper wringer roll 5 with the wringer bearing 25 rods 6. The lower bearing rod operates in a stationary bearing 7. The upper bearing rod operates in a movable bearing 8. A spring 9 operates on the upper bearing 8 to put the rolls under pressure.

The sides of the base are extended at 1a overlapping 30 the bottoms of the stiles. The top web of the base is turned up in the form of a lip 10 which extends along the inner face of the inner wall of the side stile and forms a re-enforcement 35 for the inner wall of the stile.

A bearing plate 11 is arranged under the bearing 40 7. It is provided with a brace 12 which has a projection 13 at its lower end adapted to extend into a perforation 14 in the lip 10. The brace 45 12 is joined with the plate 11. In fact the two are formed from a single plate bent at 15. This bend places the point of engagement at the bend with the outer wall of the stile below the point of engagement of the inner end of the plate with 45 the inner wall of the stile.

In assembling the frame, the plate is inserted 50 in the top of the stile and readily drops down to position, the inner end of the plate 11 reaching the shoulder formed by the lip 10, the parts at this point assuming the position shown in Fig. 4. With added pressure on the plate, the walls and 55 plate are sprung permitting the point of contact of the plate to move downwardly so that the plane through the lines of engagement of the plate with the walls of the stile is inclined, the

outer line of engagement being the lower. This forcing the point of engagement at the end from a point above the horizontal to a point below locks the plate in position so that it requires a real pressure to loosen it. As the plate is rocked 60 from the position shown in Fig. 4 to the final position, the projection 13 is moved into the opening 14 so that the brace has a definite rest and engagement with the front wall of the stile.

The plate 11 with its brace makes a very rigid 65 and substantial support for the bearing block 7. Thus the surfaces of the bearing block are maintained in a line with the roll shaft. This is important in that it is desirable to have the bearing surfaces in bearing relation to the shaft 70 throughout the width of the block.

What I claim as new is:—

1. In a wringer, the combination of a frame comprising a box-shaped stile; a lower roll bearing in said stile; a support in said stile for said bearing comprising a bearing plate extending crosswise of said stile; and a brace for the plate extending across the stile below the plate from one side of the bearing plate to the opposite wall 80 of the stile.

2. In a wringer, the combination of a frame comprising a box-shaped stile; a lower roll bearing in said stile; a support in said stile for said bearing comprising a bearing plate extending crosswise of and insertable into the end of the 85 stile; and a brace for the plate extending across the stile below the plate.

3. In a wringer, the combination of a frame comprising a base; a box-shaped stile on the base, the base having an upwardly extending lip 90 extending upwardly along the inner surface of the wall of the stile; a lower roll bearing in said stile; a support in said stile for said bearing comprising a bearing plate, one end of said plate resting on the upper edge of the lip, the opposite end 95 of the plate engaging the opposite wall; and a brace extending downwardly from the plate and engaging the wall under the part of the plate engaging the upper edge of the lip.

4. In a wringer, the combination of a frame 100 comprising a base; a box-shaped stile on the base, the base having an upwardly extending lip extending upwardly along the inner surface of the wall of the stile; a lower roll bearing in said stile; a support in said stile for said bearing comprising a bearing plate, one end of said plate resting on the upper edge of the lip, the opposite end of the plate engaging the opposite wall; and a brace extending downwardly from the plate and 105 engaging the wall under the part of the plate en- 110

gaging the upper edge of the lip, said brace being movable into engagement by the rocking of the plate.

5. In a wringer, the combination of a frame comprising a base; a box-shaped stile secured on the base, the base having a lip extending upwardly along the inner surface of a wall of the stile, said lip having a shoulder below its upper edge; a lower roll bearing in the stile; and 10 a support in said stile for said bearing comprising a bearing plate, one end of said plate resting on the upper edge of the lip, the opposite edge of said plate being joined with a brace extending downwardly and forwardly, said brace having a 15 projection entering the perforation in the lip.

6. In a wringer, the combination of a frame comprising a base; a box-shaped stile secured on the base, the base having a lip extending upwardly along the inner surface of a wall of the 20 stile, said lip having a shoulder below its upper edge; a lower roll bearing in the stile; and a support in said stile for said bearing comprising a bearing plate, one end of said plate resting on the upper edge of the lip, the opposite edge of 25 said plate being joined with a brace extending downwardly and forwardly, said brace having a projection entering the perforation in the lip, the point of engagement of said plate with the wall of the stile opposite the lip being below the edge of 30 the lip.

7. In a wringer, the combination of a frame comprising a box-shaped stile; a lower roll bearing in said stile; a support in said stile for said bearing comprising a bearing plate insertable 35 into the stile and having a length engaging the opposing walls of the stile with the plate in an inclined position and movable under pressure into a more nearly horizontal position yieldingly locking the plate in the stile; and a brace below the 40

bearing plate and resting against that wall of the stile engaged by the lower end of the plate while inclined.

8. In a wringer, the combination of a frame comprising a box-shaped stile; a lower roll bearing in said stile; a support in said stile for said bearing comprising a bearing plate insertable into the stile and having a length engaging the opposing walls of the stile with the plate in an inclined position and movable under pressure into a more nearly horizontal position yieldingly locking the plate in the stile; and a brace joining the plate at the end which is highest while the plate is inclined and extending downwardly and across the stile to the opposing wall. 80 85 90

9. In a wringer, the combination of a frame comprising a box-shaped stile; a lower roll bearing in said stile; a support in said stile for said bearing comprising a bearing plate insertable into the stile and having a length engaging the opposing walls of the stile with the plate in an inclined position and movable under pressure into a more nearly horizontal position yieldingly locking the plate in the stile; and a brace joining the plate at the end which is highest while the plate 95 100 105 is inclined and extending downwardly and across the stile to the opposing wall and having a shoul- dered engagement with said opposing wall.

10. In a wringer, the combination of a frame comprising a box-shaped stile; a lower roll bearing in said stile; a support in said stile for said bearing comprising a bearing plate insertable into the stile and having a length engaging the opposing walls of the stile with the plate in an inclined position and movable under pressure into a more nearly horizontal position yieldingly locking the plate in the stile; and a brace below the bearing plate. 105 110 115
